George Starkey, of New York, N.Y.

Letters Patent No. 2233-Dated Dec. 2-1863.

Design for a Statuette.

The schedule referred to in these Letters Patent and making part of the same.

To all whom it may concern.

Bent knoweth that I, George Starkey, of No. 596, Broadway, in the City, County and State of New York, have invented a new and useful improvement in Design for a Statuette, and do hereby declare that the following is a full, clear and exact description thereof, which will enable others skilled in the art to make and use the same, reference being had to the accompanying drawings, forming part of this specification, in which

Figure 1 is a side view of a statuette containing my design. Figure 2 is a front view.

The design consists of a female figure intended to represent an American Slave Woman, having a turban on her head, and plain garments hanging down from the waist to a point below her knees. The rest of her person is naked. The said garments are partly held up by being turned over her left arm. Her hands are clasped in front of her breast and her eyes and face are directed upwards.

At her side is a whipping post, whose top is broken off and having a broken rope attached to it lies behind the figure. A whip is suspended from it. The whole design is meant to be emblematical of the emancipation of the slaves by Proclamation of the President.

On the front of the pedestal of the statuette are the words and figures "1 of January 1863."

I claim the design as shown and described.
